DESK STAND FOR A STAPLER OR THE LIKE

Leda K. Holley, 1890 Kalmia St.,
Sweet Home, Oreg. 97386

Filed Oct. 6, 1967, Ser. No. 8,887

Term of patent 14 years

(Cl. D74—5)

FIG. 1 is a side perspective view of a desk stand for a stapler or the like showing my new design, the side opposite thereto being a mirror image thereof; and

FIG. 2 is a side elevational view thereof.

The broken line showing of the stapler in this view being merely for illustrative purposes.

I claim:

The ornamental design for a desk stand for a stapler or the like, substantially as shown and described.
